CLAIM

We claim the ornamental design for an illuminated toy light saber, as shown and described.

DESCRIPTION

FIG. 1 is a perspective view of an illuminated toy light saber, showing our new design;

FIG. 2 is an enlarged perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a right-side elevational view thereof; and,

FIG. 8 is a left-side elevational view thereof.

The saber portion of FIGS. 2 and 5–8 are shown broken away for the ease and clarity of illustration.

1 Claim, 2 Drawing Sheets
